US0D1094179S

(12) **United States Design Patent** (10) Patent No.: **US D1,094,179 S**
(45) Date of Patent: ** Sep. 23, 2025

(54) **ZIPPER SLIDER**

(71) Applicant: **IDEAL FASTENER (GUANGDONG) INDUSTRIES LTD.**, Zhaoqing (CN)

(72) Inventors: **Wei Qiu**, Zhaoqing (CN); **Zongjian Lyu**, Zhaoqing (CN); **Guoliang Qiu**, Zhaoqing (CN); **Qijun Luo**, Zhaoqing (CN); **Franklin Chi Yen Hung**, Zhaoqing (CN)

(**) Term: **15 Years**

(21) Appl. No.: **35/521,246**

(22) Filed: **May 13, 2024**

(80) **Hague Agreement Data**

Int. Filing Date: **May 13, 2024**

Int. Reg. No.: **DM/237561**

Int. Reg. Date: **May 13, 2024**

Int. Reg. Pub. Date: **Jun. 14, 2024**

(30) **Foreign Application Priority Data**

Dec. 22, 2023 (CN) 202330847874.0
Feb. 23, 2024 (CN) 202430093722.0

CLAIM

The ornamental design for a zipper slider as shown and described.

DESCRIPTION

5. Zipper slider

5.1: Front

5.2: Back

5.3: Left

5.4: Right

(Continued)

5.5: Top
5.6: Bottom
5.7: Perspective

1 Claim, 7 Drawing Sheets
